BAGGING MACHINE WITH TROUGH LEADING TO AN APERTURED ROTATABLE PLATE HAVING BAG SPREADING MEANS

Elmer Dale Austin, Umatilla, Fla.

Application June 10, 1947, Serial No. 753,765

9 Claims. (Cl. 226—59)

1

This invention relates to improvements in apparatus for holding bags while being filled, and particularly to apparatus for holding a plurality of net or woven fiber bags and for directing citrus fruit or the like into said bags to fill the same.

One object of this invention is to provide a device which will hold open the mouths of a plurality of bags, and successively to present each open bag to a trough down which citrus fruit travels into the open bag.

Another object of this invention is to provide a bag filling device where the full bags may be removed while an empty bag is being filled and a new bag speedily and securely attached thereon for ready positioning for subsequent filling.

A further object of this invention is to provide a device for filling citrus fruits into net bags or the like which may be transported readily to various locations where the fruit is sorted and packed, and which is simple to operate and inexpensive to construct.

Another object of this invention is to provide a bagging machine which automatically prohibits fruit from rolling into the bag while a full bag is being removed from the filling trough and an empty bag is being placed in position for filling.

Other objects and advantages of this invention will become apparent as the description proceeds and is considered in connection with the accompanying drawings wherein is illustrated one embodiment of this invention in which:

Fig. 1 is a top view of the improved bagging machine embodying this invention.

Fig. 2 is a side elevation thereof and showing the rotating table to which a plurality of bags to be filled with citrus fruit or the like are hung and the relation of the delivery tray thereto.

Fig. 3 is an enlarged top plan view of the rotating table embodied in this invention.

Fig. 4 is an enlarged side elevation, partly in section, of the bag holding mechanism in position to hold a bag with the mouth open, and the mechanism for holding the table from turning.

Fig. 5 is a cross section therethrough showing the bag holding member, and taken on the line 5—5 of Fig. 4.

Referring now to the drawings wherein for the purpose of illustration is shown a preferred embodiment of the invention, the numerals 6, 7, 8 and 9 represent openings in a circular plate 10 through which fruit drops into suspended awaiting bags 11. The plate 10 constitutes a rotating table for supporting the bags.

The plate 10 is rotatably mounted or journaled

2

upon a suitable upright shaft 12, and is held in a vertical position by a collar 13 (Fig. 4) which may contain any type of anti-friction bearing desired. It is to be understood that the plate 10 is adapted to rotate freely around the shaft 12.

A plate or base 14 is affixed to the shaft 12 by a lock collar 15 and is made vertically adjustable by adjustment of the collar, so that it can be moved up and down the shaft 12 for the purpose of supporting the bottoms of various sized bags 11. The plate 14 preferably is made of heavy sheet metal but can be made of any material desired. The shaft 12 may be pointed on its lower end, as shown, to be driven into the ground for supporting the same or may carry a base or the like (not shown), which supports the bagging machine in its entirety in an upright position.

Carried upon the upper end of the shaft 12 and locked thereto by a collar 16 or other suitable means is one end 19 of a V-shaped trough or delivery tray 17 provided with a central opening 18 slightly larger in diameter than, and which coincides respectively with, the openings 6, 7, 8 and 9 in the rotating plate 10. The trough 17 is inclined at a slight angle downward toward the shaft 12 so that the fruit will roll down the trough through the opening 18 and thence through one of the openings 6 to 9 in the plate 10 into an awaiting bag 11. The opposite end of the tray 17 is supported in any suitable manner to hold the tray in this inclined position.

The tray 17 has a bearing bracket 19 fixed to the forward end thereof by means of which the tray is fixed on the shaft 12 by the collar 16. A frame 20 is mounted by trunnions 24 on the bearing bracket 19, which frame 20 has a downwardly depending block bar 21, approximately equal in length to the inside of the delivery tray 17, as shown in Fig. 1. The frame 20 is pivoted for vertical swinging movement relative to the tray 17.

The end of the frame 20, opposite the block bar 21, has a downwardly depending stay pin 22 which coacts with and enters selectively into holes 23 spaced circumferentially and adjacent the axis of the plate 10 as shown.

When the frame 20 is in an upright or locked position as shown in Figs. 2 and 4, the stay pin 22 will engage one of the holes 23 and lock the rotating plate 10 in position with one of the openings 6, 7, 8 or 9 in juxtaposition below the opening 18 in the tray 17. When a bag is filled and it is desired to place an empty bag in position for filling, the block bar 21 is moved downward by a handle 25 into the tray 17, as shown.

in Fig. 1, thereby stopping the movement of the fruit down the incline of the tray, and at the same time the stay pin 22 is moved out of the hole 23 in plate 10 allowing the plate to rotate until an empty bag 11 is carried beneath the hole 18, whence the block bar 21 is again raised into the upper position shown in Figs. 2 and 4, where the filling process is repeated.

Turning now to a detailed description of the bag holding device, numerals 26 and 27 (Fig. 3) designate downwardly depending bag hooks welded or otherwise rigidly affixed to the underside of plate 10 adjacent each of the openings 6, 7, 8 and 9 as shown in Figs. 3, 4 and 5. Disposed radially inward from the bag hooks 26 and 27 and on the opposite side of the respective openings 6, 7, 8 and 9, and likewise on the underside of the plate 10, are lugs 28 and 29 to which a second set of bag hooks 30 and 31 are pivotally attached by means of cross rod 32 or other suitable means. The bag hooks 30 and 31 are jointed together by means of the cross rod 32 fixed thereto which provides a uniform swinging movement for these hooks. The set of hooks 30 and 31 are right angular in shape, as shown in Fig. 4. All of the hooks 26, 27, 30 and 31 are provided with hooks 33 upon their ends, for engaging the tops of the bag 11 as shown in Fig. 4.

Pivoted carried by the hook 26 is a hand lever 34. A connecting bar or link 35 is pivotally connected between the lever 34 and the pivoted hook 30. A tension spring 36 is connected to the hook 30 by means of a pin 37 and has the opposite end connected to the underside of the plate 10 by means of an eyelet 38 or the like, as shown in Figs. 3, 4 and 5. It is to be noted that this spring is of the customary toggle action and swings past the center of the cross bar 32 to hold the hooks 30 and 31 either open to receive an empty bag or remove a full bag as the case may be, or closed to hold the mouth of the bag open, in a toggle or snap action.

The operation of this device is as follows: Bags 11 are fixed to the underside of plate 10 by first raising or pulling out the lever 34 to a substantially horizontal position. This throws the bag hooks 30 and 31 outward or away from the shaft 12, to the left in Fig. 4. An empty bag then is hooked onto the hooks 33 of the four bag hooks 26, 27, 30 and 31. The lever 34 then is pulled down, which throws the hooks 30 and 31 inward toward the shaft 12. This in turn tightens the bag 11 at four corners firmly onto the hooks 26, 27, 30 and 31. The bag thus supported from the underside of the plate 10 is directly below one of the openings 6, 7, 8 or 9. Three other bags are similarly placed on the remaining hooks adjacent each of the other openings.

Fruit or other articles to be bagged then is moved by gravity down the inclined tray 17, through the opening 18 and thence through one of the openings 6, 7, 8 or 9, positioned therebelow, until the bag is filled.

After a bag is filled, the handle 25 is pulled down as shown in Fig. 1. This causes the block bar 21 to move into the tray 17 as a bridge, and it stops further movement of the fruit. At the same time, the stay pin 22 is pulled out of the hole 23 which permits plate 10 to be rotated until an empty bag is swung into position beneath the hole 18 in the tray 17. After the bag is in position the handle 25 then is swung upward, removing the block bar 21 from the tray and thus permitting the fruit or articles to be bagged to move down the inclined tray and

through the opening 18. At the same time, the stay pin 22 again is set in one of the holes 23 to hold the plate 10 from rotating.

While the invention is illustrated and described in one embodiment, variations and changes may be made therein, except as specified in the claims.

I claim:

1. A bagging machine comprising an inclined chute tray having a delivery portion at one end thereof, a carriage adjacent the tray, a block bar mounted for movement downwardly into the tray in position to keep material from reaching the delivery portion, means mounting the carriage for rotation relative to the tray, means mounted on the carriage in position for supporting a bag thereon to hold the bag in receiving position relative to the tray delivery portion, and means connected with the block bar for locking the carriage against rotation in a receiving position when the block bar is moved outwardly of the tray.

2. A bagging machine comprising an inclined chute tray having a delivery portion at one end thereof, a carriage adjacent the tray, means mounting the carriage for rotation relative thereto, means mounted on the carriage in position for supporting a bag thereon to hold the bag in receiving position relative to the tray delivery portion, and means connected with the block bar for locking the carriage against rotation in a receiving position, and means operatively connected with said locking means and mounted for downward movement into the chute for blocking the movement of material through the tray to the discharge portion thereof when said carriage locking means is out of holding relation with the carriage.

3. A bagging machine comprising an inclined delivery tray having a discharge opening adapted to receive therethrough articles to be bagged, an upright support affixed to the lower end of the tray, a plate rotatably carried below the inclined tray by the upright support, said plate having openings therein which are adapted to be singularly associated with the opening in the tray, bag supporting means depending from the plate, locking means carried by the upright support adapted to prevent the plate from being moved while the bags are being filled and having means connected therewith to prevent the articles from moving down the tray while the plate is rotated, and a bag bottom supporting plate carried by the upright support.

4. A bagging machine comprising an inclined delivery tray having an opening therein located adjacent the lower end of the tray, said opening being adapted to receive therethrough articles to be bagged, a vertical upright support affixed to the lower end of the tray, supporting means carried by the support adapted to permit transport of the machine from place to place, a plate rotatably carried below the inclined tray by the upright support, said plate having openings located circumferentially therein in position to be singularly associated with the opening in the tray and through which the articles to be bagged may pass, a frame pivoted adjacent one end to the upright support above the delivery tray, means to prevent rotation of the rotating plate and carried upon one end of the pivoted frame, and a block bar carried upon the opposite end of the frame.

5. A bagging machine comprising an inclined delivery tray having an opening therein located adjacent the lower end of the tray, said opening being adapted to receive therethrough articles

to be bagged, a vertical upright support affixed to the lower end of the tray, supporting means carried by the support adapted to permit transport of the machine from place to place, a plate rotatably carried below the inclined tray by the upright support, said plate having openings located circumferentially therein in position to be singularly associated with the opening in the tray and through which the articles to be bagged may pass, a frame pivoted adjacent one end to the upright support above the delivery tray, means to prevent rotation of the rotating plate and carried upon one end of the pivoted frame, a block bar carried upon the opposite end of the frame, a pair of depending bag hooks rigidly affixed to the supporting plate associated with each opening in the plate, a pair of pivoted depending bag hooks associated with each opening in the plate, a bar connecting the pivoted hooks together, an operating lever pivoted to one of the rigid depending bag hooks, a link connecting the lever with the pivoted hooks, a tension spring connected between the pivoted hooks and the supporting plate adapted to move the pivoted hooks from a bag holding to a bag releasing position with a positive snap action, and a vertically adjustable bag bottom supporting means carried upon the vertical upright support.

6. A bagging machine comprising an inclined delivery tray having an opening therein adapted to receive therethrough articles to be bagged, an upright support affixed to the lower end of the tray, a bag supporting plate rotatably carried by the upright support, a pivoted frame pivotally carried by the upright support, means to prevent rotation of the bag supporting plate carried by one end of the frame, and a block bar carried upon the opposite end of the frame in position to enter the tray and prevent passage of articles therealong to the discharge opening.

7. A bagging machine comprising an inclined delivery chute having a discharge opening adapted to direct articles therefrom for bagging, a bag supporting member rotatably connected with the chute in position to receive articles therefrom, said member having an opening therein, a frame pivotally mounted for swinging movement relative to the chute, a pin carried by the frame in position to enter the opening in the member upon movement of the frame in one direction, and a block bar carried by the frame and in position

to enter the chute upon movement of the frame in the opposite direction to prevent passage of articles to the discharge opening.

5 8. A bagging machine comprising an inclined delivery chute having a discharge opening arranged to deliver articles therefrom, an upright support, a bag supporting member rotatably mounted on said support in position to receive articles from said discharge opening, a frame pivotally mounted on the upright support, said bag supporting member having an opening therein, a pin fixed to the frame at one end thereof in position to enter the opening upon swinging movement of the frame in one direction to prevent rotation of said bag supporting member, and a transverse block bar carried by the frame in position to enter the chute upon swinging movement of the frame in the opposite direction to prevent passage of articles to the discharge opening.
